Primary Examiner — George D. Kirschbaum(74) *Attorney, Agent, or Firm* — Payam Moradian(57) **CLAIM**

I claim the ornamental design for an automobile wheel, as shown and described.

DESCRIPTION

FIG. 1 is a front view of an automobile wheel, showing my new design;

FIG. 2 is a perspective view thereof;

FIG. 3 is a front view of a second embodiment of an automobile wheel, showing my new design; and,

FIG. 4 is a perspective view of FIG. 3.

The broken line showing of the rear of the rim is included for the purpose of illustrating environmental subject matter and folios no part of the claimed design.

1 Claim, 4 Drawing Sheets(56)
